UNITED STATES PATENT OFFICE.

ARTHUR JOSEPH CULP, OF CLANTON, ALABAMA.

ENGINE.

1,376,516.

Specification of Letters Patent.

Patented May 3, 1921.

Application filed July 24, 1918. Serial No. 246,518.

To all whom it may concern:

Be it known that I, ARTHUR J. CULP, a citizen of the United States, residing at Clanton, in the county of Chilton and State 5 of Alabama, have invented certain new and useful Improvements in Engines, of which the following is a specification, reference being had to the accompanying drawings.

This invention relates to improvements 10 in engines, and particularly to certain improvements in and additions to the engine illustrated in my Patent No. 1,211,095, patented January 2nd, 1917.

The object of the present invention is to 15 provide improved means whereby compressed air may be used in forming the fuel charge for an internal combustion engine, and provide means whereby air at a constant pressure may be forced at intervals 20 into the intake end of the internal combustion cylinder along with the fuel, and provide means whereby a constant pressure of air may be maintained on the upper surface of liquid fuel in the fuel tank, this 25 air having the same pressure as the air which is forced in the engine.

A further object is to provide a compressed air tank in which air is compressed by the power of the engine, and provide a 30 charge forming means, provide a tank connected to the charge forming means and to the compressed air tank and having therein means for maintaining in the second named tank air at a constant pressure, and 35 provide a fuel tank connected to the charge forming means and to the second named tank.

Other objects will appear in the course 40 of the following description.

My invention is illustrated in the accompanying drawings, wherein:—

Figure 1 is a side elevation of an engine constructed in accordance with my invention;

Fig. 2 is a vertical longitudinal sectional view thereof;

Fig. 3 is a detailed fragmentary elevation of the main shaft and the sprocket wheels showing the clutch therefor;

Fig. 4 is an end elevation of the engine;

Fig. 5 is a section on the line 5—5 of Fig. 2;

Fig. 6 is a detailed fragmentary elevation of the engine cylinder and the eccentric actuated valve and ignition operated mechanism thereof;

Fig. 7 is a fragmentary elevation of the governor and allied parts;

Fig. 8 is a sectional view of the governor on the line 8—8 of Fig. 7.

Figs. 9, 10 and 11 are diagrammatic views of the internal combustion engine and the mechanism for controlling the opening of the inlet and exhaust valves and for controlling ignition, the several figures showing 60 the several different events.

Referring to these drawings, and particularly to Figs. 1 and 4, 10 designates the base of the engine upon which is mounted a suitable supporting frame comprising the 70 vertical standards 11 having suitable cross braces, the longitudinal beams 12 and the transversely extending saddles 13, which support the explosive engine cylinder 14 and the compressor cylinder or pump 15. 75 Longitudinal beams 16 connect the standards 11 and the upper ends of the standards carry saddles 17 and the upper ends of the standards are upwardly flared as at 18 to support a compressed air storage tank 80 or reservoir 19 which is formed, as illustrated in Fig. 2, with a jacket 20.

Mounted upon the beam 16 in suitable bearings is the transverse crank shaft 21, the cranked portion 21^a of which is connected by a piston rod 22 to the piston 23 of the cylinder 14. A piston rod 24 connects the crank 21^a to the piston 25 of the air compressor 15. This piston 25 is formed with inwardly opening air inlet 90 valves 26 held in place by springs 27. Upon the outward stroke of the piston 25, the valves 26 are opened, allowing air to enter the interior of the compressor 15 and upon the inward stroke of the piston, the valves 95 will close and the air compressed within the compressor will be forced out through the pipe or duct 28 into the storage tank 19. This pipe line 28 is provided with a check valve 29 of any usual or suitable character.

Mounted upon the beams 12 in suitable bearings are the transversely extending rotor shafts 30 carrying rotors 31 mounted in communicating casings 32. These casings are connected by the duct 33 and the rotors are provided with a plurality of blades 34, each blade having a radial face and a face which is tangential to the rotor. It will be noted from Fig. 2 that the rotors 105 are not mounted concentrically in the casings 32 but that the ends of the

blades move in approximate contact with the upper wall of the housing 32 but are spaced from the lower wall thereof for the purpose which will be later stated.

5 From the storage tank 19 leads a pipe 35 which opens into the first rotor casing 32. Disposed within the pipe 35 is the governing valve 36 which is a rotatable valve on the order of a throttle valve and disposed 10 between the valve 36 and the rotor casing 32 is a cut-off valve 37. The operation and purpose of these valves will be later stated.

The cylinder 14 is jacketed as at 38 and the compressed air after it has done work 15 upon the rotors 31 is discharged into a pipe 39 which opens into the jacket 38 and from thence this cool exhaust air is conducted by means of a pipe 40 to the jacket 20. The cylinder 14 is provided in its head with the 20 usual spark plug 41 illustrated in Figs. 9, 10 and 11, and with a charge inlet pipe 42 and with an exhaust valve 43. The exhaust valve is formed with a spindle 44 extending out through the casing 45 and the exhaust 25 valve is held to its seat by means of a spring 46. The casing 45 has a pipe 47 leading from it which discharges into the pipe 40. Thus when the valve 43 is opened by mechanism which will be hereafter described, the 30 air discharging through the pipe 40 into the jacket 20 and out through the final exhaust 48 acts to draw the exhaust gases from the cylinder 14 so that just as soon as the valve 43 is opened, the exhaust gases will be sucked 35 out from the cylinder and the cylinder thoroughly scavenged.

From the storage tank 19, a pipe 49 leads into a pressure regulating chamber 50. Disposed within the pipe 49 is a pressure regulating valve 51, this valve being in the form of a throttle valve and being rotated to a more or less open position or a closed position by an arm 52 connected by a link 53 to a lever 54 mounted upon a bracket 55 attached to the chamber 50. The upper portion of this chamber 50 is formed to provide a cylinder 56 which opens into the chamber 50 and disposed in this cylinder is a piston 57 having a rod 58 which passes out through 50 an opening in the cylinder 56 and carries a pin and roller at its upper end engaging in the slot 59 formed in the lever 54. A spring 60 urges the lever 54 downward and the valve to an open position, while the 55 pressure of air within the chamber 50, acting on the piston 57 acts to urge the lever 52 upward thereby urging the valve to a closed position. Thus when the pressure within the chamber 50 is reduced beyond a 60 predetermined amount, the piston 57 will fall and the valve will be opened to allow compressed air to enter from the storage tank 19 into the chamber 50 until the pressure within this chamber has raised to such 65 a degree that the piston 57 will be raised,

thus closing the valve 51 and cutting off the supply of air. I have thus provided means for automatically regulating the pressure within the chamber 50 and maintaining this pressure constant at all times. By regulating the tension of the spring 60, any desired pressure may be maintained within the chamber 50.

Disposed below the chamber 50 is a gasoline tank or container 61 and leading from the chamber 50 is a pipe 62 having a branch 63 which leads into the upper end of the gasoline container 61. From the gasoline container 61 extends a pipe 64 having therein a needle valve 65, this pipe 64 opening 75 into a pipe 66 which leads into the cylinder 14 and constitutes a charge inlet pipe therefor. The compressed air above the gasoline in the tank 61 therefore acts to force the gasoline or other fuel down through the 80 pipe 64 and into the pipe 66 and so into the cylinder 14, the passage of the fuel charge into the cylinder 14 being controlled by means of a valve 67 whose construction and 85 operation will be later described.

The pipe 62 has a branch 68 which extends downward into a position in line with the pipe 66 and then opens into the pipe 66 through a valve casing 69 wherein is disposed a puppet valve 70 held to its seat by 90 means of a spring 71 whose tension may be controlled by means of the wing nut 72.

Preferably a cut-off valve 73 is disposed in the pipe 63, this valve serving to shut off the air from the pipe 62 when necessary to 100 refill the gasoline container and also serves to regulate the passage of compressed air through the pipe 63 into the gasoline container. The gasoline container is provided with the usual receiving opening and duct 105 leading into the container. The valve 65 serves to regulate the flow of gasoline to the supply pipe.

The valve 70 is of considerable importance, as this valve serves to control the flow 110 of compressed air in proportion to the flow of gasoline. It will be seen that the compressed air from the chamber 50 passes out from pipe 62 and branch 68 into the pipe 66 and by tightening up the thumb nut 72, the 115 pressure of the spring 71 can be increased, thereby diminishing the flow of compressed air and thereby increasing the percentage of gasoline with relation to the compressed air so as to secure a higher percentage of 120 gasoline in the mixture. By loosening the nut 72, the flow of compressed air may be increased so as to secure a lower percentage of gasoline in the charge. This can also be secured by regulating the needle valve 65 125 and thus by controlling the valves 65 and 70, a complete control may be had of the combustible mixture or charge. The valve 67 as illustrated is a rotatable valve, normally closed, but opened at a certain period 130

in the cycle to permit the charge to pass into the cylinder 14. The means whereby this valve is operated, whereby the exhaust valve is operated and whereby the ignition 5 is secured will be described later.

The rotors 31, as illustrated in Fig. 5, are provided with laterally disposed packing rings 74 urged outward against the side wall of the housing 32 by means of the springs 10 75. I do not wish to be limited, however, to this particular construction. The shafts 30 of these rotors, as illustrated in Fig. 1, are provided with the sprocket wheels 76 and the crank shaft 21 is also provided with 15 the sprocket wheel 77 over which a sprocket chain 78 passes. This sprocket wheel 77 is loose on the crank shaft 21 but is adapted to be shifted into operative engagement therewith by means of a clutch 79 mounted 20 upon the shaft 21 and operated by means of a clutch lever 80. This shaft 21 preferably carries upon it a fly wheel 81 and a belt wheel 82, whereby power may be transmitted from the shaft.

25 The clutch 79 is not only adapted to engage the sprocket wheel 77 with the shaft 21 or disengage it therefrom but it is also adapted to engage a sprocket wheel 83 with the shaft 21. The sprocket wheel 83 has a 30 sprocket chain 84 which extends to any element which is operatively connected to the traction wheels of the machine if the engine is mounted upon a vehicle so that when running down hill or under like circumstances, the power of the traction wheel 35 may be transmitted to the shaft 21 and this power be used for operating the air compressing pump and compressing air in the tank 19, means being provided for cutting off at this time the passage of fuel to the 40 engine and stopping the action of the ignition system. Of course when the clutch 79 is in a neutral position, neither of the sprocket wheels 83 or 77 are connected to 45 the shaft and the shaft 21 is then operated entirely by the internal combustion engine 14.

The valve 37, as before stated, is a cut-off valve for cutting off the admission of 50 compressed air to the rotor casing 32. The valve 36 is for regulating the amount of compressed air actuating the rotors 31 and to this end I have shown this valve as a throttle valve having an arm 85 operatively connected to a governor of any suitable character (not shown). The valve 36 is urged to its open position by a spring 86. When the rotor increases its speed beyond a 55 predetermined point, the governor will then 60 operate in a well known manner to shift the arm 85 toward the closing position of the valve against the action of the spring 86, thus cutting down the supply of air to the rotors and thus decreasing the speed of the 65 rotors. Thus the valve 36 will be controlled

so as to keep the speed of the rotors even and at any predetermined speed. I do not wish to be limited to any particular form of valve 36, but I have shown a throttle valve for purely illustrative purposes. I 70 have not illustrated the governor for controlling this valve as this may be of any ordinary or usual type, or the valve may be connected to the governor which is used for controlling the valve 67 whereby the explosive mixture is allowed to pass into the cylinder 14 as will be later described.

The means for operating the several valves of the internal combustion engine and for the closing of the circuit through 80 the spark plug to thereby ignite the charge is as follows: Mounted upon the shaft 21 is an eccentric 87 as illustrated in Figs. 6, 9, 10 and 11. This eccentric carries the usual eccentric ring 88 from which projects an 85 arm 89, which is operatively connected to a slide 90, operating in guides 91. Pivotedly connected to the slide 90, is a rod 92 which at its rear end is connected by means of a link 93 as will be later described.

90 Mounted upon the rod 92 is a contact member 94 which coacts with an electrical contact 95 disposed normally in the path of the member 94 and which is electrically connected to the spark plug 41. The contact member 94 is electrically connected to a battery 96 through the rod 92 as will appear. Mounted upon the rod 92 is a valve actuating member 97 which coacts with an arm 98 mounted upon a shaft 99 having a 100 cranked portion connected by a link 100 to a crank on the spindle of the valve 67. A spring 101 urges the arm 96 in a direction to close the valve 67, that is, into the position shown in Fig. 9. When the rod 92 105 moves toward the left in Fig. 9, this member 97 will engage the arm 96 and rotate the valve 67 to its open position.

102 Mounted upon the rod 92 is a member 102 which is adapted to ride upward upon a 110 roller 103 carried upon a swinging rod 104. This rod extends transversely of the engine and is pivoted upon the frame of the engine at 105 and the roller as illustrated in Fig. 6, operates in a guide 106. In Figs. 9, 10 and 115 11, however, the swinging arm 104 is shown as being disposed vertically. This is because these Figs. 9, 10 and 11 are diagrammatic. When the member 102 strikes the roller 103 the member 102 rides up on the 120 roller 103 so as to lift the rod 92 and lift the valve operating member 97 away from the arm 96, thus releasing this arm so that the spring 101 returns the valve 67 to its closed position. The swinging rod 104 operatively engages the stem of the exhaust valve 43 and mounted upon the rod 92 is an 125 adjustable member 107 which upon the return of the rod 92, as illustrated in Fig. 9, engages the roller 103 and shifts it toward 130

the right in Fig. 9, thus opening the exhaust valve.

It will thus be seen that as the piston 23 moves inward into the cylinder 14, as illustrated in Fig. 10, the eccentric shifts the rod 92 inward and at the proper time the adjustable member 97 engages the valve operating lever 98 and opens the valve 67, whereupon a charge of compressed air and gas enters the cylinder 14. As soon as the valve 67 has been opened to admit the charge, the adjustable member 102 rides up over the roller 103, thus lifting the member 97 out of its engagement with the lever 98 and releasing the valve 67 which immediately closes. As soon as this occurs and the piston 23 has advanced sufficiently far into the cylinder 14, the contact member 94 engages with the contact member 95 and the circuit is closed between the battery 96, the roller 103 to which the battery is connected on one side, the rod 92, the contact member 94, the contact member 95 and the spark plug. Of course the usual induction coil may be used in this circuit in the usual manner to secure a high tension current. I have not illustrated this, however, as this is obvious to any electrician. As soon as the charge has been exploded the piston 23 moves outward, and the rod 92 moving toward the right in Fig. 9 causes the member 107 to engage with the roller 103 shifting the swinging rod 104 toward the right in Fig. 9 and forcing open the exhaust valve. As before explained, the exhaust air passing through the rotor casing, through the jacket 20 and specifically through the passage 40 acts to draw out the exhaust gases from the cylinder 14 when this valve is open. As before stated, the link 93 is connected to a governor and thus when the engine speeds up beyond a predetermined point, this governor acts to lift the link 93 and this acts, as illustrated in dotted lines in Fig. 11, to lift the rod 92 to such a height that the several members 94 and 97 will not strike the parts with which they coact. Thus the inlet valve 67 will not be opened and the circuit through the spark plug will not be closed. As soon as the engine has slowed down to a proper speed, the rod 92 will be lowered and will resume its proper functions. The governing mechanism is illustrated in Figs. 7 and 8. Mounted upon the shaft 21 is the fly wheel 81 and mounted upon the spokes of this fly wheel are the governor arms 108. These arms carry upon them weights 109 urged toward the axial center of the shaft by the springs 110 and the opposite ends of these arms are operatively connected to a sliding wedge 111 which coacts with the adjacent end of a lever 112. This lever is pivoted as at 113 upon any suitable bracket or support and its opposite end is connected to the link 93 as

illustrated in Fig. 7. Mounted upon the lever is an adjustable weight 114. This weight is adjustable so as to counter-balance the opposite end of the lever 112 and urge it upward against the conical roller 111. 70

The general operation of this invention is as follows: To start the engine the valve 51 is closed and air is pumped into the chamber 50 through an inlet opening 50a by an ordinary air pump until a sufficient pressure 75 is secured in the chamber 50 to start the engine. Gasolene is, of course, disposed in the container 61. Then the fly wheel is turned on the crank shaft 21 and the explosive engine started in the usual manner thereby. 80 After proper pressure has been secured in the storage chamber 19, the valve 51 is released and connected to the controlling link 53. The engine will then operate automatically. 85

When the pressure in the chamber 50 decreases beyond a certain point, the piston 57 will descend allowing the valve 51 to open and the pressure to be increased in the chamber 50. The compressed air in the 90 chamber 50 will force the gasolene out through the pipe 64 controlled by the valve 65 and the branch 68 will carry compressed air to the pipe 66. The valve 67 is opened automatically, as previously described, so 95 that a charge under pressure is forced into the cylinder 14. The ignition circuit is then completed in the manner stated and the charge is fired and when the piston has been forced out to its fullest extent the valve 43 100 is opened and the exhaust is carried out through the pipe 47 by the air passing through the pipe 40. At the same time that the explosive engine is operating and the pump 25 is operating to force air into the 105 tank 19, the compressed air in 19 is passing into the housing 32 and acting on the rotors therein so that the power of the compressed air is used for operating rotors which assist in the driving of the shaft 21. By using 110 two rotors, I obtain a double effect with a single charge of compressed air and without the necessity of increasing the size of a rotor which would be necessary in case only a single rotor was used, thus doing away with 115 the necessity of increasing the charge in order to secure this double effect. It is obvious that by lifting the rod 92 in the manner heretofore described the explosive engine may be stopped. The piston, of course, 120 will reciprocate but without any explosion of the charge and inasmuch as the rotors are geared to the shaft 21, the rotors will continue to drive the compressing piston just so long as the air in 19 is compressed to a 125 sufficient degree to drive the rotors and thus the rotors will operate the compressor until the pressure in the tank recedes beyond a predetermined point. A weight 114 on the governor lever 112 is adjustable toward or 130

from the pivot pin 113 and is also shiftable to the opposite side of the fulcrum 113 to thereby cause that end of the lever connected with the end 93 to raise and thus lift the 5 rod 92 to the position shown in dotted lines in Fig. 11 and thus render the explosive engine inoperative so that the clutch illustrated in Fig. 3 may be used to connect the shaft 21 to the traction wheels of the machine, provided the engine is mounted upon 10 a vehicle.

It will be noted in Fig. 2 that the bottom sections of the motor casing, as before stated, are spaced from the rotors so as to 15 give the compressed air an under-shot action on the working faces of the rotors, as shown. I do not wish to be limited to the details of construction illustrated and it is to be understood that suitable bearings are to be provided for the rotated parts and that any desired valves may be used operating on the principle described and that the engine may be mounted in a different form of frame 20 than that illustrated. The details of construction and arrangement of parts may, 25 therefore, be varied in many ways without departing from the spirit of my invention as defined in the appended claims.

It is to be understood that the valves 36, 30 37, 51, 65 and 73 are conventionally shown and that regular cut-off valves will be used where it is desired to cut off entirely the flow of fluid through a pipe, and that any suitable type of regulating valve may be 35 used where it is necessary to control the amount of flow through a pipe or conduit.

It will be noted that one of the important objects secured by my mechanism is to provide means whereby air can be compressed 40 and heated so that the air can be successfully used as a motive power, and that a further object which is attained is to compress and store air by an internal combustion engine, which air constitutes part of the fuel 45 of the engine.

I claim:—

1. A mechanism of the character described including an explosive engine having a cylinder provided with an inlet pipe, an air 50 compressor driven by the explosive engine, a storage tank into which the air compressor discharges, a pressure regulating tank into which the storage tank discharges, a pressure controlled valve controlling the admission 55 of air from the storage tank to the pressure

regulating tank, a pipe connecting the pressure regulating tank to the inlet pipe, a spring retracted valve normally preventing the passage of air under pressure into the inlet pipe, a fuel tank operatively connected 60 to the pressure regulating tank, to receive air therefrom, and connected to the inlet pipe between the said spring retracted valve in the inlet pipe and the cylinder and provided with a feed regulating valve, and an 65 intermittently operated admission valve mounted in the inlet pipe adjacent the cylinder.

2. A mechanism of the character described including an explosive engine having an inlet pipe, an air intake pipe, an air compressor operated by said engine, a pressure regulating tank receiving air from the air compressor and having a valve controlling the admission of compressed air to the pressure 70 regulating tank and maintaining a pre-determined pressure therein, a fuel tank connected to the inlet pipe of the engine, an air pipe extending from the pressure regulating tank to the fuel tank to cause the discharge of fuel therefrom, an air pipe extending from the pressure regulating tank to said intake pipe of the engine, a valve in the intake pipe opening upon the suction stroke of the engine to establish communication 75 between the pressure regulating tank and said intake pipe, and means for regulating the pressure required to open said valve.

3. A mechanism of the character described 80 including an explosive engine having an intake pipe, a fuel tank therefor having a pipe connection to the intake pipe, a valve for regulating the passage of fuel from the fuel tank to the intake pipe, and pipes communicating with the fuel tank and with the intake pipe of the engine connected to a source 85 of air under pressure, a valve opening upon the suction stroke of the engine and controlling passage from said source of compressed 90 air to the intake pipe, and the pipe leading from the fuel tank opening into the intake pipe between the air pipe and the engine.

In testimony whereof I hereunto affix my signature in the presence of two witnesses. 105
